QUINCY A. BRACKETT, OF SPRINGFIELD, MASSACHUSETTS, ASSIGNOR TO WESTINGHOUSE ELECTRIC & MANUFACTURING COMPANY, A CORPORATION OF PENNSYLVANIA.

GRID LEAK.

Application filed September 29, 1921. Serial No. 504,126.

My invention relates to wireless telegraphy and more especially to grid leaks which are employed in connection with electron tubes.

The object of my invention is to provide 5 a vacuum-tube device embodying means for adjusting the rate of leakage of the charge which accumulates on the grid of such devices.

In the operation of three-electrode tubes 10 as detectors or as oscillation generators, it is desirable to control the rate of leakage of the negative charge which builds up on the grids of the tubes during normal operation.

15 Heretofore, it has been customary to determine the rate of leakage of the charge by shunting the grid and the filament of the tube with a resistor of relatively high value. Such resistors have taken the form of carbon 20 impregnated paper or of metallic particles held together by means of vitreous material. A disadvantage in the use of resistors of such types, however, is the difficulty of obtaining, in quantity production, resistors 25 having similar characteristics. For example, resistors constructed under like conditions have been found to vary in effective value by many thousands of ohms. Furthermore, such grid-leak devices, as have been 30 brought to my attention, have been found subject to the phenomenon of ageing, that is to say, their effective value has changed materially with time, and they are likewise 35 seriously affected by atmospheric changes.

According to my invention, I provide, in 40 the ordinary three-electrode tube, an auxiliary hot cathode which may be caused to control the rate of leakage of the charge from the grid of the tube. The auxiliary 45 hot cathode is electrically connected to the grid of the three-electrode tube and is so disposed that the main hot cathode of the tube serves as an anode for said auxiliary hot cathode when the grid assumes a negative charge. By adjusting the temperature of said auxiliary hot cathode, the rate of leakage of the charge from the grid may readily be controlled.

50 Other objects of my invention, as well as details of construction, whereby my inven-

tion may be practiced, will be apparent from the following description referring to the accompanying drawing, wherein;

Figure 1 is a diagrammatic view of an electron tube embodying my invention, as 55 applied to a wireless receiving system; and

Fig. 2 is a similar view, but showing my invention as applied to a wireless transmission system.

Referring to Fig. 1, I have shown an 60 antenna 1 connected to a ground 2 through a primary winding 3 of a coupling transformer 4. A secondary winding 5 of the coupling transformer 4 has its opposite terminals shunted by a condenser 6 to form 65 a resonant circuit 7, and is connected by conductors 8 and 9 to a grid 11 and to a hot cathode 12, respectively, of a thermionic device 13. The conductor 8 has included in circuit therewith a condenser 14 for causing the grid 11 to assume a negative potential upon the receipt of signal impulses in the antenna 1.

The thermionic device 13 comprises a 70 customary anode 15, the grid 11, the hot 75 cathode 12, which is energized from a source of energy 16, and, in addition, a second hot cathode 17 which is energized by means of a source of energy 18 through a variable resistor 19. The auxiliary hot cathode 17 is connected to the grid 11 by means of a conductor 20 through a radio-frequency choke coil 21. While the cathode 17 is shown as disposed immediately adjacent to the main hot 80 cathode 12, it is not to be limited to such 85 position. Upon the grid 11 assuming a negative potential, the main hot cathode 12 serves as an anode for the auxiliary electron-emitting cathode 17. A plate-filament circuit comprises an indicating device 22 and 90 a source of energy 23.

In Fig. 2, the thermionic device 13 is connected in a well known oscillation generator system. A plate-filament circuit includes a portion 24 of a tuning coil 25 and a 95 variable condenser 26, and may be energized by means of a source of direct-current energy 27 which is connected to opposite terminals of the condenser 26 through reactors 28 and 29.

A grid-filament circuit includes a condenser 31 for causing the grid 11 to assume a negative potential and a feed-back coil 32 which is inductively related to a portion 5 of the coupling coil 25. The auxiliary cathode 17 has been shown disposed within the tube 13, similarly to that shown in Fig. 1, and is energized from a source of energy 32 through a resistor 33 and a pair of radio-frequency choke coils 34, 35. The filament 12 may be energized from a source of energy 36 through a resistor 37. A conductor 35 serves to connect the grid 11 and the auxiliary filament 17.

15 In order to simplify the drawing in so far as possible, I have omitted means for controlling the transmission of the radio-frequency energy which is generated by the system. As will be readily understood by 20 those skilled in the art, however, any of the well known systems of modulation may be employed.

In operation, referring to Fig. 1, during the receipt of incoming signal impulses, 25 such, for example, as those radiated from a spark transmitter, each wave train thereof tends to cause the grid 11 to assume a negative potential. In order that each wave train may produce a maximum change in 30 the current traversing the plate-filament circuit of the tube, that is, maximum effect on the indicating device 22, it is necessary that the negative charge be dissipated between successive incoming wave trains. In my in- 35 vention, the desired result just mentioned is readily effected by adjusting the temperature of the auxiliary hot cathode 17 through the variable resistor 19 to an optimum value giving the largest current variations in the 40 plate-filament circuit of the tube.

Referring to Fig. 2, upon adjusting the constants of the plate-filament and the grid-filament circuits to their proper value, 45 radio-frequency currents are generated by the tube in accordance with well known theories. In this application, the rate of leakage of the negative charges, which are built up on the grid by reason of the condenser 31, may again be readily controlled 50 by varying the temperature of the cathode 17.

While I have described only two modifications of my invention, it will be obvious to those skilled in the art that it is susceptible 55 of many minor changes, alterations and modifications without departing from the spirit thereof. I desire, therefore, that only such limitations shall be imposed thereon as are indicated by the prior art or are specifically set forth in the appended claims.

I claim as my invention:

1. In an evacuated electric device, an anode, an electron-emitting cathode, a grid electrode, a second electron-emitting cathode 65 and means for maintaining said last-men-

tioned cathode at grid potential, whereby said cathodes serve as electrodes for providing a grid-leak path.

2. In a radio device, an evacuated vessel, 70 an anode, a grid and two heated electrodes therein, separate sources of heating current for said heated electrodes, means cooperating with said anode, grid and one of said heated electrodes, for impressing radio-frequency potential on said grid, a conductive 75 connection between said grid and the other of said heated electrodes, whereby the space between said heated electrodes constitutes a grid leak, and a radio-frequency choke coil between said grid and the source of heating 80 current for said second electrode.

3. In a wireless system, an electron tube comprising an anode, a cathode, a grid and a second cathode immediately adjacent to 85 said first-mentioned cathode, a conductor connecting said grid and said second cathode, means associated with said electrodes for causing said grid to assume a negative potential, means associating said second cathode with said grid to cause the space between said cathodes to constitute a grid leak, and means associated with said second cathode for adjusting the rate of leakage of the charge from said grid.

4. In a wireless system, an electron tube 90 comprising an anode, a cathode, a grid and a second cathode immediately adjacent to said first-mentioned cathode, a conductor connecting said grid and said second cathode, means associated with said electron 100 tube for causing said grid to accumulate a negative charge, means associating said second cathode with said grid to cause the space between said cathodes to constitute a grid leak, and means for adjusting the temperature of said second cathode, whereby 105 the rate of leakage of the charge from said grid may be selectively controlled.

5. In a wireless system, an electron tube 110 comprising an anode, a cathode, a grid and a second cathode immediately adjacent to said first-mentioned cathode, a conductor connecting said grid and said second cathode, a circuit connecting said grid and said first-mentioned cathode and embodying a 115 source of energization and a series connected condenser, and means for adjusting the temperature of said second cathode, whereby the impedance of the space-current path between said cathodes may be controlled to correspondingly vary the rate of leakage of a charge from said grid.

6. The combination with an evacuated electric device having two electron-emitting electrodes and an anode, of means for establishing a space-current flow between one of said electrodes and said anode, a grid circuit for controlling said space-current flow, a grid condenser included in said circuit, and connections for including said electron-emitting 125 130

electrodes in a grid-leak path shunting said condenser.

7. A vacuum-tube oscillation-generator of the feed-back type including a vacuum tube having two electron emitting electrodes and an anode, means for establishing a space-current flow between one of said electrodes and said anode, a grid circuit for controlling

said space-current flow, a grid condenser included in said circuit and connections for 10 including said electron-emitting electrodes in a grid-leak path shunting said condenser.

In testimony whereof, I have hereunto subscribed my name this twenty-sixth day of August 1921.

QUINCY A. BRACKETT.
